UNITED STATES PATENT OFFICE.

HARRY S. LEE, OF PLYMOUTH, MICHIGAN.

APPARATUS AND METHOD OF COATING MOLDS WITH CARBON.

Application filed February 16, 1925. Serial No. 9,528.

This invention relates to a method and apparatus of coating matrices of permanent molds with carbon, and more specifically pertains to an improved method for evenly distributing the coating of carbon over the matrix of the mold.

The present method of coating molds with carbon is the passing of a mold past a ball of incomplete combustion flame, the carbon being deposited on the mold. This works fairly well, but it is found that quite often the carbon is deposited unevenly and results in certain portions of the mold having a thicker coating of carbon than the remaining portion of the mold. This results in an uneven casting, as the thicker portions of carbon make depressions in the casting and quite often these difficulties necessitate the junking of the casting. With my process the carbon is evenly distributed and there is no possible chance of an uneven coating of carbon being deposited on the mold and thereby it reduces the number of castings which are wasted.

One of the objects of my improved method is the moving of a flame along the surface of the mold at a uniform rate of speed and maintaining the flame at a constant distance from the surface of the matrix of the mold, which is to be coated with the carbon. Another object is the association of my method for permanent mold machines wherein a plurality of molds are continually moving along a certain line. My method may be easily adapted to such a machine by moving the flame in conjunction with the moving molds.

This method may be applied to various types of molding machines wherein the molds are moved or conveyed in a straight line or are located on a revolving table, such as described in pending application Serial No. 4,744.

In the drawings:

Fig. 1 is a plan view of a portion of a permanent mold machine, showing one form of mechanism for performing my method.

Fig. 2 is a section on the line 2—2 of Fig. 1, which shows one form of apparatus for passing the flame along the surface of the matrix of the mold.

Fig. 3 is a section on the line 3—3 of Fig. 1.

Carried on conveyor chains or belts *a* are the supports *b*. These supports carry the guide rods *c*, which support the mold carriers

d and *e*, the carrier *d* being held stationary near the extremity of the guide rods and the inner carrier *e* being slidably guided on the guide rods. These mold carriers each carry the mold halves *f* which are provided with a mold cavity or matrix *g*, the surface of which it is desired to coat with an even coating of carbon, which serves to insulate the mold from the molten metal and also serves as a parting material permitting the automatic discharge of the casting when the same hardens. The inner movable mold carrier *e* is provided with the inwardly extending tongue *h*, which carries the roller *i* on its inner end. This roller *i* is adapted to be engaged in the cam groove *j* so that as the molds are moved longitudinally the roller rides in the cam groove, thereby moving the mold carrier *e* to separate or close the molds.

Supported on the super-structure *k*, which is composed of any suitably designed steel framework, is a triangular track *m*, which has one side *n* inclined at an angle to the horizontal. Guided in these tracks is a flame apparatus *o*, which is provided with the rollers *p* engaging in the tracks. This flame apparatus supports the horizontal gas pipe *r*, and the depending T-shaped gas distributing pipe *s* provided with the burner tips *t*, for projecting the flame laterally against the surface of the mold in a fan-shaped flame. Carried by the gas pipe *r* is a depending trip arm *u*, which is engaged by the trip *v* carried on the movable supports *b*. As the molds are moved along, the trip *v* engages the arm *u* and moves the flame carrying apparatus to the right, as viewed in Fig. 2, thereby causing the rollers *p* to ride up the inclined track *n*, thereby raising the burner tips *t* into the dotted line position, as shown in Fig. 2.

The upper end of the inclined track *n* is closed by a trap door *w*, which allows the rollers *p* to pass by. Now when the rollers reach this upper position, carrying the flame carrier with it, the arm *u* is raised and permits the trip *v* to pass under, thereby releasing the arm and allowing the coil tension spring *x*, which is secured to a portion of the superstructure and to the flame apparatus, to return the flame apparatus along the horizontal track *y*, thereby holding the flame or burner tip in its upper level until the same returns to approximately its original position over the following pair of

2
molds, whereupon the same is allowed to drop down the vertical track 1 and to drop the flame in the following set of molds, whereupon the flame apparatus is again 5 moved for repeating the operation for coating the following set of molds.

The burner tips are flattened out so as to provide a fan-shaped flame, which is directed against the matrix of the mold and 10 coats a portion of the matrix with a coat of carbon. This flame is moved by the mechanism above described, and is raised slowly but at a uniform speed, thereby moving the flame along the surface of the matrix 15 of the mold at a uniform and constant speed. This exposes the surface of the matrix of the mold to a flame of equal intensity for a constant length of time, and as a result a uniform coating of carbon is deposited thereon 20 and avoids the possibility of some of the surface having a thicker coating of carbon than the remaining portion.

Obviously this fan-shaped flame could be varied within certain limits as a fan-shaped 25 flame such as shown in this apparatus is more particularly adapted for coating a mold provided with a circular form of matrix. Where flat surfaces are desired to be coated with carbon, several jets could be utilized for shooting a thin sheet of flame against the surface, the width of the flame depending upon the amount of surface to be coated. The essential feature is the moving of a 35 sheet of flame along the surface of the matrix of a mold in a direction at right angles to the plane of the flame, thereby exposing all portions of the surface of the matrix to the flame for the same length of time, and to expose all parts of the surface 40 to a flame of equal intensity.

What I claim is:

1. The method of depositing an even coat of carbon over the surface of the matrix of a mold, which comprises the moving of a 45 single incomplete combustion sheet flame

having a greater relative width than depth at a uniform speed along the entire surface of the matrix of said mold in a direction which is at right angles to the plane of said sheet flame, and parallel to the surface to be coated. 50

2. The method of depositing an even coat of carbon over the surface of the matrix of a mold, which comprises the moving at a constant speed by said mold of a single incomplete combustion relatively thin sheet flame having a uniform heat intensity along the entire surface of the matrix of said mold and moving in a direction which is 55 at right angles to the plane of said sheet flame and parallel to the surface to be coated. 60

3. In an apparatus for coating molds with carbon, the combination of a burner provided with means for projecting a sheet flame, and means for moving said burner along the surface of said mold at right angles to the plane of the sheet flame.

4. In an apparatus for coating molds with carbon, the combination of a burner provided with a burner tip having a jet opening which is relatively long and narrow for the purpose of projecting a sheet flame, and means for moving said burner along the surface of said mold at right angles to the plane of the sheet flame. 70

5. In an apparatus for coating molds with carbon, the combination of a burner provided with means for projecting a fan-shaped sheet flame, said means located at a point substantially equi-distant from all points in the mold surface in the plane of the flame, and means for moving said burner parallel to the surface of the mold and at right angles to the plane of the fan-shaped sheet flame. 85

In testimony whereof I have affixed my signature.

HARRY S. LEE.
